UNITED STATES PATENT OFFICE.

BRUNO B. CHOINSKI, OF MILWAUKEE, WISCONSIN.

COMBINED HOT-AIR AND HOT-WATER HEATER.

Application filed January 12, 1927. Serial No. 160,554.

This invention relates to improvements in heaters for dwellings and other buildings, with particular reference to that class of heaters known as combined hot water and hot air heating systems.

The object of this invention is to provide means for utilizing the heat of the fuel to the best possible advantage. More particularly stated, the object of this invention is to provide means whereby a water container or boiler may be so disposed with reference to the burning fuel and the hot air chamber of the furnace as to form a helical passage for the smoke and gases of combustion, the walls of which are so disposed as to effect a maximum transfer of heat to the respective media, i. e., to the water and to the air in the air jacket.

The drawing is a vertical sectional view of a heater embodying my invention, drawn generally to a central plane but illustrating the water chamber or boiler and its helical baffles in full except as to parts which are indicated as broken away to show the interior.

The combustion chamber 10 of the improved heater may be of any ordinary construction, having a grate 11, and an ash pit 12 being provided below the grate. Centrally disposed above the combustion chamber 10 and extending downwardly into it to some extent, a water chamber or boiler 13 is provided. This water chamber or boiler is substantially in the form of a truncated inverted cone, the bottom 14 of which is preferably dished or conically tapered upwardly from its margins to a central apex 15. To protect the bottom 14 from direct contact with the fuel in the combustion chamber 10, a removable false bottom 16 is employed. This will preferably be made of cast metal conforming generally to the contour of the bottom 14 but having a marginal flange 17 provided with bayonet joint slots 18 whereby it may be rotatively engaged with connecting pipe 19 and projections 20, whereby the false bottom may be suspended in position of substantial contact with the bottom 14.

The water chamber or boiler 13 is provided with a series of hemispherical heat absorbing knobs 24, preferably formed by pressing the material of which the wall is composed outwardly by a drawing or embossing operation performed upon the blank before rolling the blank upon a mandrel to

form the wall of the chamber. The boiler is also preferably formed with a helical flange 25 extending from its bottom to a point near the top and provided with apertures 26 at suitable intervals. This flange may be secured to the wall of the chamber by any suitable means, such for example, as a welding operation. The flange progressively narrows in width from the bottom to the top in proportion to the increase in the diameter of the boiler chamber, whereby the outer margin of the flange may be fitted to the cylindrical wall 28 of the heater. The cylindrical wall 28 is closed at the top by a suitable head piece 29, and a smoke flue or pipe 30 extends laterally from its upper end portion. An outer jacket, preferably having also a cylindrical wall 31 has a conically tapered truncated cap 32 of the ordinary contour employed for hot air furnaces and forming a jacket cavity or space 33 for hot air, outlets being indicated at 34 to which service pipes may be connected and extended to the apartments to be heated.

The water container or boiler is provided with one or more service pipes 36 leading from its upper portion to radiators (not shown) in the apartments to be heated. The return flow pipe 37 leads to the lower portion of the boiler in the ordinary manner and the flow is controlled by the valve 38. Another pipe 39 may operate as a drain pipe, this pipe being provided with a valve at 40. The air inlet for the air jacket cavity 33 is indicated at 41.

It will be observed that the passage for the smoke and gases of combustion is a helical passage which progressively diminishes in capacity in a definite proportion to the distance from the firepot or combustion chamber. The convergence of the boiler wall 13 toward the cylindrical wall 28 may be such that the helical flue will be proportioned in capacity to the volume of the gases, said gases diminishing in volume in proportion to their loss of heat. Therefore, the pressure of the gases upon the walls of the passage will remain substantially constant. The drawing is not intended to indicate the exact degree of convergence necessary to any given installation, the degree of convergence being an engineering problem to be solved in accordance with well known formulæ when the size of the heater, the character of the fuel, and other conditions under which it is to operate are known.

In the operation of the improved heater, the smoke and gases of combustion will of course follow the helical passage 44 except as to those portions which pass through the 5 apertures 26. The portions which pass through the apertures 26 form ascending jets which tend to break up the continuity of the current of heated gas, and increase the 10 tendency for all portions thereof to be brought into contact with the inner and outer walls of the passage, whereby maximum heat transfer through such walls is promoted. Owing to the fact that the gases follow a 15 helical path, centrifugal force will be developed which tend to cause them to press against the outer wall 28 and thereby promote heat transfer into the air in the encircling annular chamber 33. However, the convergence of the wall of the water chamber 20 13 toward the wall 28 is such as to maintain a substantially uniform density of the gases of combustion from bottom to top, except for a slight increase in density along the wall 28 due to centrifugal force. Therefore, the 25 pressure of the molecules upon the water chamber is generally maintained and kept uniform from the bottom to the top of that chamber. This is a very important feature of the invention in that a maximum transference of heat may be effected, the heat of the water, the gases of combustion and of the air in the chamber 33, approaching equalization in the upper part of the furnace, although the rapid flow of air through the air 30 35 jacket cavity tends to keep the temperature of the air considerably lower than that of the gases of combustion, with a corresponding increased rapidity of heat transfer to the air.

40 I claim:

1. A combined hot air and hot water heater, comprising the combination with a combustion chamber, of a hot water container in the form of an inverted truncated cone 45 encircled by a helical flange which progressive-

ly narrows in width upwardly, a cylindrical wall enclosing the outer margins of said flange and forming with the walls of the water container and the flange a helical smoke passage, an outer jacket spaced from 50 said wall to form an air chamber and provided with inlet and outlet apertures in its lower and upper portions respectively, and service pipe and return connections for said water container.

2. A hot air heater provided with a combustion chamber and an air jacket and having a water container centrally disposed above the combustion chamber and provided with downwardly converging walls, said 60 downwardly converging walls being spaced from the inner wall of the air jacket and provided with baffle flanges forming an air passage extending upwardly along a generally helical line about the water container, 65 said flange being apertured at suitable intervals to promote ascending jets across the helical path of the main current.

3. In a combined hot water and hot air furnace, the combination with a combustion chamber, of a superposed water container, an enclosing air chamber, and an intervening smoke flue which progressively narrows from bottom to top in general proportion to the diminishing volume of gases of combustion, due to loss of heat.

4. In a combined hot water and hot air furnace, the combination with a combustion chamber, of a superposed water container, an enclosing air chamber, and an intervening smoke flue which progressively narrows from bottom to top in general proportion to the diminishing volume of gases of combustion, due to loss of heat, said smoke flue being of a generally helical form and encircling the water container and provided with a smoke outlet at its upper end, the lower end being open to the combustion chamber.

BRUNO B. CHOINSKI.
